UNITED STATES PATENT OFFICE

2,539,543

EXTRACTOR

Frank J. Leuthner, Sharpsville, Pa.

Application March 3, 1949, Serial No. 79,385

3 Claims. (Cl. 22—93)

1

This invention relates to extractors, especially extractors for extracting cores from molds in foundry work. It has to do with improvements in extractors which enhance their utility and improve their operating characteristics.

My invention is applicable generally to the extraction of cores from foundry molds in cases in which a core may be pushed out of one end of a mold or flask by exerting pressure on the core at the opposite end of the mold or flask. I have developed the invention in apparatus designed specifically for removing the cores from flasks after making hollow castings such as ingot molds and for purposes of explanation and illustration I shall describe the invention as embodied in an extractor for extracting cores from flasks in which ingot molds are cast.

Ingot molds are cast in hollow generally tubular flasks in which are positioned cores for forming the ingot cavities. When an ingot mold is to be cast the flask is set up, the core is introduced into it in proper position and molten metal is poured into the flask about the core to form the ingot mold. The core may be collapsible or non-collapsible as preferred although normally collapsible cores are used in the casting of ingot molds. The interior of the flask and the exterior of the core may be lined with sand before the molten metal is poured. After the casting has solidified the core is removed from the casting and the casting is removed from the flask. In ingot mold casting it is customary to employ elongated cores having pins projecting upwardly above the tops of the flasks, the ingot molds being cast in inverted position.

When an ingot mold has been cast in apparatus as above described as well known in the art pressure is brought to bear on the top of the pin which projects upwardly from the core and at the same time the flask is pulled upwardly so that the core is extracted downwardly out of the flask and casting. Extractors for thus extracting cores from flasks have been used for very many years. A substantial number of patents have issued covering such extractors. One such patent is my own Patent No. 1,881,055 which for present purposes may be taken as representative of the prior art.

A difficulty which has been encountered through the years with extractors of the type shown in my said patent and in other prior patents is that when the extractor has been lowered to the extent that its weight is partially carried by the core and the crane hook is further lowered, the extractor levers in addition to turn-

2

ing down about the axes of their pivotal connections with the extractor also tend to flop sideways, carrying with them the chains and hooks which are to be connected under the flask flange.

5 But at precisely the same time workmen are endeavoring to grasp the extractor hooks and hook them under the flask flange. The movement of the extractor levers transversely of their normal planes of operation is uncontrollable and does not follow any regular pattern. One time the levers may flop one way and the next time the opposite way.

The core pins of the various cores used in a foundry are of no uniform length and the non-uniformity in the length of the core pins adds to the uncertainty as to the paths which the extractor levers will follow in moving from their initial vertical position when first lowered by the overhead crane to their generally horizontal position (see Figure 1 of my said patent) when the extractor hooks are hooked under the flask flange. The uncontrollable movement of the extractor levers has resulted in danger to the workmen whose duty it is to grasp the extractor hooks and place them under the flask flange. On many occasions weird and unpredictable movements of the extractor levers have resulted in portions of the extractor mechanism striking workmen on their heads or the upper portions of their bodies injuring them, sometimes seriously. This condition has existed for many years and has been recognized and deplored by those most highly skilled in the art, but prior to my present invention no solution has been found.

35 I have discovered how to obviate the undesirable uncontrollable movement of the extractor levers and the danger incident to such movement. I have discovered that the extractor levers should have a wider bearing span on the pivot pins through which they are connected to the extractor pin. I preferably utilize extractor levers having opposed spaced apart end portions embracing the portions of the extractor pin to which they are respectively pivoted. Preferably each lever is made up of two spaced apart members which are suitably fastened together by spacing and connecting means so that the ends of the levers straddle the portions of the extractor pins to which they are respectively pivoted, and the means carrying the extractor hooks may likewise be positioned between the levers and fastened thereto. My extractor insures movement of the extractor levers more normally in planes perpendicular to the axes of the pivot pins through which they are pivoted to the ex-

tractor pin than was the case with the old extractors which employed single rather than double levers. With my extractor construction the movement of the levers is relatively regular and uniform and the workman can grasp the extractor hooks and place them under the flask flange with relatively little danger of being injured by uncontrolled movement of the levers.

The differences in structure between my extractor and the extractors which have been used for generations are slight yet they are of fundamental importance because of the entirely different operating characteristics which they impart to the extractor. The results which are achieved by my new extractor have been sought for at least two generations to my knowledge but no one has conceived how to bring them about.

Other details, objects and advantages of the invention will become apparent as the following description of a present preferred embodiment thereof proceeds.

In the accompanying drawings I have shown a present preferred embodiment of the invention in which

Figure 1 is a side elevational view of an extractor;

Figure 2 is a plan view of one of the double levers of the extractor;

Figure 3 is an elevational view of the double lever shown in Figure 2;

Figure 4 is an elevational view of the extractor pin; and

Figure 5 is a top plan view of the extractor pin.

Referring now more particularly to the drawings, the extractor pin comprises a cylindrical body portion 2 and a head 3 integral with the body portion 2 and having opposed laterally projecting single thickness ears 4. Each ear 4 has a bore 5 therethrough. At opposite sides of the head 3 vertical projecting guides 6 are provided.

A centering member 7 cooperates with the extractor pin, the centering member having therein and extending upwardly from the bottom thereof a cylindrical cavity 8 of such cross-section as to receive the core pin and also the body portion 2 of the extractor pin may be of the same cross-section. At its bottom the centering member 7 has a base portion 9 adapted when the centering member is positioned over the core pin to rest upon the top of the casting in the flask. The centering member 7 has opposed slots 10 open at the top for receiving the ears 4 of the extractor pin and also has opposed grooves 11 for receiving the guides 6 of the extractor pin. Two cross pins 12 bridge the top of the centering member 7 to keep the centering member from dropping away from the core pin, the cross pins 12 resting atop the body portion 3 of the core pin when the extractor is supported free of the core. When the extractor is lowered into operative position the core pin is received within the lower part of the cylindrical cavity 8 and the base portion 9 of the centering member 7 rests on the top of the casting. The extractor pin moves down within the cavity 8 until its bottom bears upon the top of the core pin. The centering member 7 may initially be placed over the core pin by hand and maintains the extractor pin in cooperative relationship with the core pin during use of the extractor.

Pivoted to each of the ears 4 of the core pin is a double lever 13 as shown in Figures 2 and 3. Each of the double levers 13 consists of two similar lever members 14 disposed in opposed spaced apart relation, being so maintained by spacers 15

suitably fastened between the lever members as by rivets 16. Each double lever 13 has at each end opposed spaced apart end portions 17 each having a hole 18 therein for receiving a pivot pin.

Each of the double levers 13 is positioned with one end in cooperative relationship with one of the ears 4 of the extractor pin, the opposed spaced apart end portions 17 at one end of the double lever lying on opposite sides of the ear with the holes 18 coaxial with the hole 5 of the ear. A pivot pin 19 passes through the holes 18 and 5 and thus pivotally connects each double lever 13 to the extractor pin. The lever members 14 bear on the pivot pin 19 at points on opposite sides of the ear.

Each of the double levers 13 has holes 20 in its lever members 14 through which by a pivot pin 21 a link 22 is pivoted to the double lever. Each link 22 has its upper end disposed between the lever members 14 and at its lower end has a vertically elongated slot 23 in which is disposed the saddle 24 of a hook 25 adapted to be positioned beneath the flask flange.

At the outer end of each lever 13 a link 26 has a portion disposed between the lever members 14 and pivoted thereto by pivot pin 27, chains 28 connecting the links 26 with a large ring 29 adapted to be disposed over the hook of an overhead crane.

When the extractor is to be used it is carried by the overhead crane with the crane hook passing through the ring 29 to a position above the flask containing the core and the ingot mold cast therein. When the extractor is being carried to position the chains 28 and double levers 13 hang down vertically, the centering member 7 being supported by the extractor pin by the cross pins 12 which rest on the upper surface of the extractor pin. The extractor is lowered until the centering member 7 receives in its cavity 8 the upwardly projecting core pin. When the centering member 7 is in position its base portion 9 rests on the upper surface of the casting. Then as the extractor is lowered the bottom of the extractor pin seats on the top of the core pin, after which part of the weight of the extractor is carried by the core as the crane hook continues its downward movement.

As the crane hook continues its downward movement the levers 13 swing downwardly substantially in planes normal to the axes of the pivot pins 19 until the levers are in generally horizontal position, at which time the hooks 25 are grasped by workmen who place them under the flask flange. The downward swinging movement of the double levers is comparatively regular and predictable and the levers do not flop sidewise as was the case with the single levers previously employed. The danger to the workmen is thus largely eliminated and the work facilitated.

When the hooks 25 have been hooked under the flask flange the crane hook is raised, resulting in pressing downwardly on the extractor pin and pulling upwardly on the hooks 25 until the core is stripped from the flask.

The relatively wide bearing of the double levers 13 on the pivot pins 19 appears to result in the improved operation as above described although I am not sure of the theory of action. Whatever the theory may be, it is a fact that my extractor does not have the disadvantages of the prior extractors as explained above and has the characteristics of regular and controlled move-

ments eliminating the hazard to the workman which has previously always existed. My extractor also brings about more efficient operation as because of its relatively controlled and predictable movements it is much easier and quicker to use than the prior extractors.

While I have shown and described a present preferred embodiment of the invention it is to be distinctly understood that the invention is not limited thereto but may be otherwise variously embodied within the scope of the following claims.

I claim:

1. An extractor comprising means for exerting downward pressure on a core, a centering device for centering the first mentioned means with respect to the core, opposed levers each pivoted to the first mentioned means for pivotal movement relatively thereto generally in a common vertical plane, means connected with the ends of the levers remote from the first mentioned means for raising said ends of the levers and lifting devices extending downwardly from the respective levers intermediate the ends thereof for exerting upward pressure on a flask surrounding the core when said ends of the levers are raised, the extractor being characterized by each of the lifting devices being an elongated depending link having its upper end pivoted directly to the lever with which it is connected for rotation relatively to the lever about a horizontal axis and having a hook connected directly with the depending link at its lower end, the hook having inwardly facing means adapted to hook under a portion of the flask.

2. An extractor comprising means for exerting downward pressure on a core, a centering device for centering the first mentioned means with respect to the core, opposed levers each pivoted to the first mentioned means for pivotal movement relatively thereto generally in a common vertical plane, means connected with the ends of the levers remote from the first mentioned means for raising said ends of the levers and lifting devices extending downwardly from the respective levers intermediate the ends thereof for exerting upward pressure on a flask surrounding the core when said ends of the levers are raised, the extractor being characterized by each of the lifting devices being an elongated depending link hav-

ing its upper end pivoted directly to the lever with which it is connected for rotation relatively to the lever about a horizontal axis and having a slot adjacent its lower end with a hook having a portion extending within the slot and having inwardly facing means adapted to hook under a portion of the flask.

3. An extractor comprising means for exerting downward pressure on a core, a centering device for centering the first mentioned means with respect to the core, opposed levers each pivoted to the first mentioned means for pivotal movement relatively thereto generally in a common vertical plane, means connected with the ends of the levers remote from the first mentioned means for raising said ends of the levers and lifting devices extending downwardly from the respective levers intermediate the ends thereof for exerting upward pressure on a flask surrounding the core when said ends of the levers are raised, the extractor being characterized by each of the opposed levers being a double lever having opposed spaced apart elongated portions with spacing means therebetween and connected therewith and each of the lifting devices being an elongated depending link having its upper end disposed between the opposed spaced apart elongated portions of the double lever with which it is connected and pivoted directly thereto for rotation relatively to the lever about a horizontal axis and having a hook connected directly with the depending link at its lower end, the hook having inwardly facing means adapted to hook under a portion of the flask.
